UNITED STATES PATENT OFFICE.

JOHN T. LOGAN, OF TEXARKANA, TEXAS.

APPARATUS FOR TREATING THE BUTT-ENDS OF POLES.

No. 838,592.

Specification of Letters Patent.

Patented Nov. 20, 1906.

Application filed March 13, 1906. Serial No. 305,865.

To all whom it may concern:

Be it known that I, JOHN T. LOGAN, a citizen of the United States, residing at Texarkana, Texas, have invented certain new and useful Improvements in Apparatus for Treating the Butt-Ends of Poles, of which the following is a specification.

This invention relates to the treatment of wood, particularly to treatment of the butt-ends of poles, and the object is to provide apparatus for treating from four to nine feet, more or less, of the butt-ends of such poles as are used for telephones, telegraph, electric lights, and the like. In treating such poles with preserving fluids it becomes necessary to heat the poles or to heat that part of the pole which is to be treated, and it is preferable to heat only that part of the pole which is to be treated. By the means hereinafter described only the parts of the poles which are to be treated—that is, the butt-end sections—will be heated. These butt-end sections are heated to the desired temperature and then suddenly treated with the preserving fluid.

Other objects and advantages will be fully explained in the following description, and the invention will be more particularly pointed out in the claims.

Reference is had to the accompanying drawings, which form a part of this application and specification.

Figure 1 is a diagrammatic view of the apparatus used to carry out the objects of this invention. Fig. 2 is a vertical section of the vat in which the butt-end portions of the poles are treated with baths of preserving fluids. Fig. 3 is a plan view of the same in horizontal section.

Similar characters of reference are used to indicate the same parts throughout the several views.

The means for carrying out the objects of this invention include a vat 1, a fluid-supply tank 2, a relief-tank 3, a steam-boiler 4, a pump 5, and engine 6, and suitable connecting-pipes and valves. The poles 7 are set endwise with the butt-ends down in the vat 1. The poles are heated with hot creosote. The creosote is heated by steam-heated pipes 8. Steam is provided for the pipes 8 by the boiler 4. The pipe 8 is bent and laid on and throughout the bottom of the vat. Bars 9, of iron or steel, are placed between the coils of the pipe 8 to prevent the poles from crushing the pipe. The creosote may be let into the vat 1 in desired

quantities by a pipe 10, which has connection with the tank 2. The pipe 10 has a cut-off valve 11. Creosote is run into the vat 1 until the creosote fills the vat to a height of four feet or to any desirable height up to ten feet or more. If more creosote is let into the vat 1 than is necessary, it may be drawn off through a pipe 13 to the vat 3. The pipe 13 is connected to the vat 1 at various heights by pipes 14, which are provided with cut-off valves 12. Any one of the pipes 14 may be opened and the creosote let out of vat 1 down to the pipe which may be opened.

When the vat 1 is provided with creosote to a determined height, the butt-ends of the poles can then be heated to that particular height without heating the poles higher, and no creosote will be wasted on the poles above the determined height. The creosote is let into the vat with the butt-ends of the poles and heated by means of the steam-heated pipe-coils 8. When the creosote is heated, it may rise higher in the vat than the determined height, but will escape through pipes 14 and 13 to the vat 3. When the butt-ends of the poles have been heated sufficiently to expand or rarefy all the air in the wood-cells in the butt-ends or butt-end sections, the hot creosote is let suddenly out of the vat 1 into a relief-tank 3 by means of a large pipe 15, which is provided with a valve 16. As soon as the hot creosote is taken from the vat 1 cold creosote is let immediately and in quick succession as possible into the vat 1 from the tank 2. The air in the wood-cells having been expanded by the hot creosote will now contract and draw the cold creosote therein. The creosote may be replaced in the tank 2 from the relief-tank 3 by the pump 5 and pipes 17 and 18. The pump 5 may be driven by the engine 6, and the engine 6 may be provided with steam from the boiler 4.

The apparatus above described is the kind of apparatus used to carry out the process described in my pending application filed February 2, 1906. It is apparent that other means may be provided for heating the butt-ends of the poles prior to receiving the treatment in the bath of the cold creosote.

Having fully described my invention, what I claim as new, and desire to secure by Letters Patent, is—

1. An apparatus for preserving end sections of poles comprising an open-top vat for containing the butt-ends of poles and a preserving fluid, coils of pipe located on the

tom of said vat for heating the preserving fluid, means for preventing the poles from crushing said pipe, means for circulating hot steam through said pipe, a supply-tank having a pipe connection with said vat, a relief-tank, a large pipe provided with a cut-off valve for sudden removal of hot fluid from said vat to said relief-tank, a pump for delivering fluid from said relief-tank to said supply-tank, and a series of overflow-pipes provided with cut-off valves and connecting said vat and said relief-tank for regulating the height of liquid in said vat.

2. In an apparatus for preserving wood provided with an open-top vat for containing the butt-ends of poles, a supply-tank, and a relief-tank; coils of pipe located in said vat, bars placed on the bottom of said vat and supporting the poles above said coils of pipe; means for heating said pipe whereby fluid in said vat may be heated, means for sudden removal of hot fluid from said vat, and means for delivering immediately cold preserving fluid from said supply-tank to said vat after the removal of hot fluid.

3. In a wood-preserving apparatus provided with an open-top vat adapted to contain the butt-ends of poles set therein and to contain a preserving fluid; means for supplying a heating fluid to said vat, a relief-tank,

means for determining the height of the heating fluid in said vat consisting of a series of pipes connected to said vat and provided with cut-off valves and connected to said relief-tank, means for heating the fluid in said vat, a large pipe for drawing the hot fluid quickly from said vat into said relief-tank, and means for refilling said vat immediately with cold preserving fluid.

4. In a wood-preserving apparatus provided with an open-top vat for containing the butt-end sections of poles and a preserving fluid; coils of heating-pipe located in said vat, bars placed between the coils of said pipe and supporting the poles above said pipe, a relief-tank, a series of pipes connected to said vat at different heights and connected to said relief-tank, a large pipe provided with a cut-off valve for quick removal of hot fluid from said vat, and means for supplying cold preserving fluid immediately to said vat to take the place of the hot fluid.

In testimony whereof I set my hand, in the presence of two witnesses, this 20th day of February, 1906.

JNO. T. LOGAN.
